UNITED STATES PATENT OFFICE.

ALBERT H. CHRISTIE, OF BRIDGEPORT, CONNECTICUT, ASSIGNOR TO THE KING MACHINE COMPANY, OF BRIDGEPORT, CONNECTICUT, A CORPORATION OF CONNECTICUT.

IRONING-MACHINE.

1,145,118.

Specification of Letters Patent.

Patented July 6, 1915.

Application filed April 22, 1914. Serial No. 833,657.

To all whom it may concern:

Be it known that I, ALBERT H. CHRISTIE, a citizen of the United States, residing at Bridgeport, in the county of Fairfield and State of Connecticut, have invented certain new and useful Improvements in Ironing-Machines, of which the following is a specification.

The present invention pertains to an improved ironing machine, the construction and advantages of which will be herein-after set forth, reference being had to the annexed drawings, wherein:

Figure 1 is a vertical sectional elevation 15 of the machine; Fig. 2 a transverse horizontal sectional view thereof; Fig. 3 a transverse vertical sectional view on the line 3—3 of Fig. 2; Fig. 4 a like view on the line 4—4 of Fig. 1; and Fig. 5 a view similar to Fig. 20 1 showing a modification of the invention.

The main object of the present invention is to produce an ironing machine simple in construction and operation, and in the use of which the hands of the operator will be 25 left free to manipulate and position the work upon the ironing-board, the board being traversed beneath the iron and lowered out of contact therewith at the end of each outward and inward movement of the board, 30 whereby the work is freed from contact with the iron and may be shifted as desired.

A further object of the invention is to provide means whereby the board may be manually lowered at any time and so held.

Referring first to the construction disclosed in Figs. 1 to 4 inclusive, 1 denotes the main frame or housing, provided with an outwardly-extending overhanging rigid arm 2, carrying at its outer end an iron 3, said iron being preferably heated by electricity as is usual. Extending outwardly from the housing at the lower portion thereof and in line with the iron-supporting arm 2, is a bed or frame extension 4, the upper portion 45 of said bed being open and provided with ways 5 in which is slidably mounted a carriage 6. Said carriage is surmounted by an ironing-board 7, from which extend downwardly two or more posts 8, the posts sliding 50 freely through openings formed in the carriage 6. Springs 9 surround said posts and serve to force the board 7 upwardly into contact with the iron 3. The board is likewise provided with a downwardly-extending arm 10, which at its lower end carries a cross-pin 55 11 upon each end of which there is mounted a roller 12. Said rollers work in slots or guideways 13, formed in the upstanding walls 14 of casting or member 15, herein-after termed the depressor frame, said frame 60 being provided with laterally-extending arms 16, the outer ends of which fit and work in guide-ways 17 formed upon the side walls of the bed 4. Frame 15 carries at its lower portion a cross-pin 18, which is engaged by the notched end of a lever 19, which extends rearwardly and is fulcrumed upon a pin secured in lugs 20 extending outwardly from the frame. A draw-rod 21 is connected to said lever 19 and to a treadle-lever 22. Lever 19, adjacent its rear end, carries an upwardly-extending arm 23, provided at its upper end with a roller 24, adapted to bear against a two-point cam 25, mounted upon and rotatable with a power 70 shaft 26, supported in suitable bearings carried by the housing 1. Shaft 26 also carries a double crank 27, to which is connected a rack-bar 28, said bar passing through a rocker-frame 29, swiveled at one end or side 75 upon a fixed shaft 30 and at its opposite side upon a laterally-extending hub 31, projecting outwardly from a pinion 32, with which the rack-bar 28 meshes. A gear 33 is secured to hub 31, said gear meshing with a 80 rack 34 formed upon or carried by the rear portion of a rod or bar 35, said bar passing through a rocker-frame 36 swiveled upon shaft 30 and hub 31, said rocker frame serving to hold rack 34 in engagement with gear 85 33. Bar 35 is pivotally connected, at its forward end, to the lower end of a rigid arm 37. The operation of the machine, thus constructed, is as follows: The operator, 90 when he desires to initially position an article upon the board, depresses treadle 22, and through rod 21, lever 19, depressor frame 15, and arm 10, draws the ironing-board 7 downwardly, placing springs 9 under compression. The board at such time may be 100 reciprocating, though if desired it may be brought to rest by throwing out the power clutch (not shown). When the article is positioned (and the power again thrown on, assuming it was thrown off) the operator 105 releases treadle 22 and the board is moved upwardly, carrying the article into contact with the iron and at the same time it is reciprocated back and forth beneath the iron by the movement of the carriage 6 to which 110

reciprocating motion is imparted through the connections above set forth, to wit, arm 37, rod 35, rack 34, gear 33, pinion 32, rack bar 28, and crank 27, the rack bar 28, as 5 will be apparent, imparting an oscillating movement to pinion 32 and consequently to the connected parts. As the carriage 6 and the board 7, sustained thereon reach or near the limit of their outward and inward movements, cam 25 comes into play, and through arm 23 depresses lever 19 and as a consequence draws the depressor frame 15 downwardly, thereby drawing the ironing-board downwardly through rollers 12, pin 11 and arm 10. Thus it will be seen that the board 15 is depressed at the end of each outward and inward stroke thereof, and drawn out of contact with the iron, at which time the operator may shift the goods laterally upon 20 the board as desired. Furthermore, it will be noted that by the employment of the treadle the degree of pressure to be exerted upon the goods may be readily regulated and controlled by simply depressing the 25 treadle to a greater or less extent, while the machine is in operation, and that a complete separation of the iron and board may be effected by a full depression of the lever.

In Fig. 5 I have shown a modification of 30 the invention. The mounting of the iron upon the slide or carriage, and the means for reciprocating the same and carrying it to and fro beneath the iron are the same as in the other construction, and said parts are 35 similarly numbered. However, instead of employing a cam, as 25, upon the power shaft 26, the depressor frame is provided with cams adapted to depress the ironing-table at the end of each stroke. The de- 40 pressor frame in this form is designated by 40, and the upstanding walls 41 thereof (of which only one is shown) are provided with longitudinally-extending slots 42, terminating at the ends in down-turned portions, 45 producing cam surfaces 43, which are adapted to coact with the rollers 12 and serve to draw the table downwardly away from the iron and to place the springs under tension as the carriage and the table supported 50 thereby reach the end of their movement in each direction. Under this construction it is necessary, of course, to provide means for preventing the depressor frame from being thrown upwardly, in order to prevent the 55 tilting of the table, and to this end a stop as 44, extends inwardly from the side walls of the bed or extension 4 and overlies the slide which works in the ways 17. The operation of this modified structure is as follows: The carriage and the board are moved 60 back and forth, beneath the overhung iron, the same as in the construction above set forth, and when the carriage nearly reaches the end of its movement in one or the other direction, as the case may be, the rollers 12

contact with cam faces 43 and the board is thereby drawn downwardly away from the iron, at which time, owing to the separation of the iron and board, the operator may shift the goods as desired. As with the 70 other construction, the ironing-board may be drawn downwardly away from the iron at any point in the travel of the board by merely depressing the treadle, which acting through the lever 19, draws the depressor 75 frame downwardly and consequently draws the ironing-board down and places the springs 9 under compression.

It will, of course, be appreciated that the board may be lowered at one end of the 80 stroke only, if so desired, this being accomplished merely by omitting one of the cam points, Fig. 1, or one of the cam faces 43, Fig. 5.

Having thus described my invention, what 85 I claim is:

1. In an ironing machine, the combination of an iron; an ironing-board; means adapted to reciprocate said board beneath said iron; and means, acting in timed relation 90 with the means for reciprocating the board, for mechanically lowering the board out of contact with said iron as the board reaches its limit of reciprocating movement.

2. In an ironing machine, the combination of an iron; an ironing-board underlying the same; means for reciprocating said board beneath the iron; means for lowering said board away from the iron at the end of the inward and outward movements thereof; 100 and independent means adapted to lower said board and to hold the same in such position.

3. In an ironing machine, the combination of an iron; an ironing-board underlying the same; means for reciprocating said board beneath the iron; means for positively lowering said board away from the iron at the end of the inward and outward strokes thereof; and manually-controlled means for 110 lowering said board away from the iron at any point in the travel of the board.

4. In an ironing machine, the combination of an iron; a spring-sustained ironing-board; means for moving said board endwise beneath said iron; and means, acting in timed relation with said last-named means, for automatically drawing said board downwardly out of contact with the iron when the same reaches the limit of its endwise 120 movement.

5. In an ironing machine, the combination of an iron; a spring-sustained ironing-board; means for reciprocating said board back and forth beneath said iron; and means 125 for automatically and positively lowering said board out of contact with the iron as the board reaches the limit of its inward and outward movements.

6. In an ironing machine, the combination 130

- of an iron; a carriage slidably mounted below the same; a spring-sustained ironing-board carried by said carriage; means for reciprocating said carriage to and fro beneath the iron; and a cam mechanism acting to lower the board away from the iron at the end of each to and fro movement of the carriage.
7. In an ironing machine, the combination of an iron; a carriage slidably mounted below the same; a spring-sustained ironing-board mounted upon said carriage; means for reciprocating said carriage and consequently the board to and fro beneath the iron; a cam mechanism acting to lower the board away from the iron at the end of each to and fro movement of the carriage; and manually-controlled means for lowering said board.
8. In an ironing machine, the combination of an iron; a bed or table located beneath the same; a carriage slidably mounted upon said bed; means for reciprocating the same; a spring-sustained ironing-board carried by said carriage; a depressor frame mounted in the bed beneath the carriage and slidable toward and from the same; connections between the frame and the board; and an associated cam mechanism to effect a downward movement of the board at the end of the inward and outward movements of the carriage.
9. In an ironing machine, the combination of an iron; a bed or table located beneath the same; a carriage slidably mounted upon said bed; means for reciprocating the same; a spring-sustained ironing-board carried by said carriage; a depressor frame mounted in the bed beneath the carriage and slidable toward and from the same; connections between said frame and the board; an associated cam mechanism to effect a downward movement of the board at the end of the inward and outward movements of the carriage; and means under the control of the operator for drawing the depressor frame downwardly.

In testimony whereof I have signed my name to this specification in the presence of two subscribing witnesses.
